(57) **CLAIM**

The ornamental design for a lens protective film as shown and described.

DESCRIPTION

FIG. 1 is a front, right, and top perspective view of a lens protective film, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view taken from encircled portion labeled “9,” in FIG. 1; and,

FIG. 10 is an enlarged view taken from encircled portion labeled “10,” in FIG. 2.

The dot-dash lines shown in FIGS. 1, 2, 9, and 10 form the boundary of the enlarged views of FIGS. 9 and 10 and form no part of the claimed design.
